TACK DISPENSER

Arthur H. Spader, Bergenfield, N. J.

Application April 20, 1948, Serial No. 22,091

6 Claims. (Cl. 1—49.7)

1

The present invention relates generally to improvements in tack dispensers, and it has particular relation to a portable dispenser that may be attached to the wrist and used to supply a continuous quantity of tacks in an aligned position, whereby the foremost tack may be readily picked up directly from the dispenser by the head of a magnetic hammer.

It is customary practice of operators using large quantities of tacks, such as carpet layers, window decorators, sign posters, upholsters and the like, who frequently require the unrestricted use of both hands, to place a quantity of loose tacks in their mouths, turn the head-end of each tack with their tongues and so position it that it can be picked up by the fingers or by the end of a conventional magnetic hammer brought adjacent their parted lips. Such practices are dangerous and insanitary, as tacks are frequently swallowed, requiring surgical removal, and disease germs are being constantly brought into contact with the mouth.

The present invention has been developed to obviate these aforementioned disadvantages, and provides a convenient portable tack dispenser that can be strapped onto the wrist of the operator or otherwise affixed to his body. The dispenser holds a quantity of tacks up to and including a complete box, and through movement of the wrist or body the dispenser is vibrated sufficiently to cause a number of said tacks to become aligned and fed forwardly to a dispensing opening where they can be easily and quickly picked up one at a time by means of the fingers or directly by the head of a conventional magnetic hammer.

One object of the invention is to provide a simple, durable and inexpensive tack dispenser which will present tacks in a convenient and advantageous manner for picking up with the head of a magnetic hammer without requiring assistance from the operator.

Another object of the invention is the provision of an efficient and simple tilting device which will prevent the tack ready to be dispensed from becoming locked in the dispenser under the overlapping head of the next succeeding tack, and which is adjustable for facilitating the delivery of tacks of different sizes having different lengths of shanks.

A further object of the invention is to provide a removable tack aligning and distributing plate, whereby the same may be removed and a smaller or larger plate substituted therefor, having slots

2

commeasurate with the size of the head of the tacks to be dispensed therein.

Other and further objects and advantages of the invention, which result in simplicity, economy and efficiency, will be apparent from the following detailed description, wherein a preferred form of embodiment of the invention is shown, reference being had for illustrative purposes to the accompanying drawings, forming a part hereof, 10 wherein like numerals indicate like parts, in which:

Figure 1 is a perspective view of a tack dispenser embodying the principles of the invention;

Figure 2 is a longitudinal sectional view, on a 15 slightly larger scale, of the task dispenser shown in Figure 1, the same having been taken substantially along the line 2—2 thereof, looking in the direction of the arrows;

Figure 3 is a cross-sectional view taken substantially along the line 3—3 of Figure 2, looking in the direction of the arrows;

Figure 4 is a sectional view taken substantially along the line 4—4 of Figure 2, looking in the direction of the arrows;

Figure 5 is another sectional view taken substantially along the line 5—5 of Figure 2, looking in the direction of the arrows;

Figure 6 is a fragmentary vertical sectional view of the tack tilting device shown in Figure 2, the 30 same having been taken substantially along the line 6—6 thereof, looking in the direction of the arrows; and

Figure 7 is another fragmentary horizontal sectional view of the tack tilting device shown in Figure 2, the same having been taken substantially along the line 7—7 thereof, looking in the direction of the arrows.

Referring now to the drawings, and particularly to Figure 1 thereof, there is shown a tack 40 dispenser 10 mounted on a strap 12 or other attaching device for securing the same to the body or wrist of an operator. The dispenser 10 consists of a unitary closed receptacle having a relatively large and rectangularly shaped lower chamber 14 and a relatively small and substantially square shaped upper chamber 16. The upper chamber 16 is provided with a removable top 18, which has downwardly projecting side flanges 20 that are provided with a suitable outwardly projecting groove 22 adapted to snap over and removably engage an outwardly projecting rib 24 formed integrally in the sides 26 thereof.

The lower chamber 14 projects outwardly beyond the upper chamber 16 adjacent one end, and a suitable cover plate or baffle 28 is mounted over

said projecting portion. The cover or baffle plate 28 also projects inwardly between the two chambers and partially closes the opening therebetween, as best shown in Figure 2. One exposed corner of the baffle plate 28 is apertured, as indicated at 30, to provide a suitable tack dispensing opening therethrough. The dispensing opening 30 is of a size sufficient to expose only the head of a single tack 32, whereby the withdrawal of tacks from the dispenser 10 is restricted to one at a time. One end of the lower chamber 14 is provided with a suitable door 34, hinged, as indicated at 35, and having its free edge bent to provide a spring lock 36 for securing the same in its closed position under the lower edge of the end 38 of the upper chamber 16.

The sides 39 and 40 of the lower chamber 14 are bent outwardly to provide opposing inwardly open channels or guideways 42 and 44 adjacent their top and immediately below the baffle plate 28. The guideways 42 and 44 are for receiving a removably mounted aligning plate 46 in spaced relation below said baffle plate 28. The tack receiving and aligning plate 46 extends over the entire top portion of the lower chamber 14, forming a division plate between the upper and lower chambers. The plate 46 is spaced high enough above the bottom 47 of the lower chamber to prevent the depending shanks of the largest tacks to be dispensed therefrom from touching the same. The tack receiving and aligning plate 46 is provided with a series of laterally spaced and longitudinally extending apertures or slots 48. Each of the slots 48 is open at its forward end and each connects with an obliquely extending feeding slot 50, which terminates under the dispensing opening 30 in the baffle plate 28. The tack receiving and aligning plate 46 is mounted removably in the lower chamber 14 so that other plates of similar construction but having slots of different widths may be substituted therefor, depending upon the size of the head of the tack to be dispensed therefrom.

A suitable tack tilting device 51 is mounted below the feeding slot 50 and in substantially vertical alignment with the dispensing opening 30. The tilting device consists of a U-shaped guard 52, having a forward edge 53 that is inclined slightly with respect to the vertical. The lower end of the forward edge 53 of the guard 52 is in substantially vertical alignment with the rear edge of the dispensing opening 30, and the upper end is substantially in axial alignment with the dispensing opening 30, as best shown in Figure 6. The guard 52 is mounted adjustably in a vertical slot 54 provided in the side 39 of the lower chamber 14 by means of a suitable pin or rivet 56. A leaf spring 58 is mounted under the outer side of the rivet head 56, and its outwardly projecting ends are adapted to engage a series of vertically spaced corrugations 62, which serve to hold the tilting device in any set position.

The upper chamber 16 of the dispenser 10 has a pair of opposed angle iron supports 64 and 66 welded or otherwise secured intermediate its sides to provide a suitable support for receiving and holding a conventional cardboard box of tacks 68 therein in spaced relation above said baffle plate 28 and the tack receiving and aligning plate 46. The cardboard box of tacks 68 should have an opening 70 cut through the bottom thereof before being placed in the dispenser to permit its contents to gravitate therefrom upon any vibrating or jiggling movement of the dispenser 10.

In the operation of the dispenser 10, the cover 18 is removed and a conventional box of tacks 68, having a suitable opening 70 in its bottom, is placed in the upper chamber 14 on the laterally spaced supports 64 and 66. The top or cover 18 is now repositioned over the sides of the upper chamber 14 to keep the box of tacks in a fixed position therein. Of course, any quantity of loose tacks 32 may be dumped into the upper chamber 16 in the absence of a conventional box of tacks. The dispenser 10 may now be fastened to the wrist of an operator or otherwise mounted on his body.

The movement of the wrist or body of the operator will cause the dispenser to shake, jiggle or vibrate, thereby causing a number of tacks 32 to fall out of the box 68 onto the receiving plate 46 and eventually cause some of their shanks to drop downwardly through the slots 48 until they are suspended by their flat heads on the top of said plate with their shanks depending therebelow. As the dispenser 10 is moved about or vibrated, some of the tacks held in an upright and suspended position in the slots 48 will have a tendency to work forwardly under the baffle plate 28 and into the feeding slot 50. The spacing between the underside of the baffle plate 28 and the top side of the receiving and aligning plate 46 is just sufficient to permit clearance of the flat tack heads, and there is little or no tendency or opportunity for the tacks once aligned and moved under the baffle plate 28 to return to the open mixing chamber 14. The vibratory motion or movement of the dispenser 10 causes the aligned tacks 32 to feed from the spaced parallel receiving and aligning slots 48 into the obliquely extending feeding slot 50 and forwardly towards the dispensing opening 30. The heads of the aligned tacks 32 may have a tendency frequently to overlap, as best shown in Figure 2, and, if this occurs at the dispensing opening 30, difficulty will be encountered in dispensing the foremost tack since the head of the succeeding tack will prevent its withdrawal. To prevent such an occurrence, the tilting device 51 engages the depending end of the tack shank forwardly of the dispensing opening, causing the tack 32 to be tilted forwardly, as best shown in Figure 6, thereby forcing the rear edge of its flat head above the head of the next overlapping tack, thereby insuring freedom therefrom in its withdrawal from the dispenser 10.

The dispensing opening 30 is just slightly larger than the flat head of the largest tack to be dispensed, and prevents more than one tack being withdrawn from the same at a time. The hinged door 34 to the lower chamber 14 permits ready access to that part of the lower chamber below the receiving and aligning plate 46 to remove any defective tacks 60 that might have fallen through the slots 48. It will be apparent from the above description that, with the employment of the dispenser 10, the operator has the full freedom of his hands, and can readily withdraw a tack 32 therefrom by the head of a conventional magnetic hammer (not shown) without dropping what he is holding in tacking position. The operator is supplied with a limited continuous quantity of tacks in an efficient and sanitary manner.

Although I have only described and illustrated in detail one form which the invention may assume, it will be readily apparent to those skilled in the art that the same is not so limited, but that various modifications may be made therein without departing from the spirit thereof.

What I claim is:

1. A tack dispenser comprising a closed receptacle separated into upper and lower chambers by a plate having a plurality of spaced parallel slots of a width to support a tack by its head with its shank projecting therethrough, said slots being in open communication at one end with a common feed slot, and a dispensing opening aligned with and spaced above said feed slot of a size sufficient to permit the withdrawal of a single tack at a time from said receptacle.

2. A tack dispenser comprising a closed receptacle separated by a plate mounted intermediate its sides into upper and lower chambers, said plate having a series of spaced tack receiving slots which are in open communication along one end with a feed slot, a dispensing opening aligned with and spaced above said feed slot of a size sufficient to permit the withdrawal of a single tack at a time from said receptacle, and a tilter mounted below said feed slot in substantial alignment with said dispensing opening for engaging the shank of the foremost tack in said feed slot to tilt the same whereby its head will be raised above the head of the next succeeding tack in the event it was overlapping the same.

3. A tack dispenser comprising a closed receptacle separated by a plate mounted intermediate its sides into upper and lower chambers, said plate having a series of spaced tack receiving slots which are in open communication along one end with a feed slot, a dispensing opening aligned with and spaced above said feed slot of a size sufficient to permit the withdrawal of a single tack at a time from said receptacle, and an adjustable tilter mounted below said feed slot in substantial alignment with said dispensing opening for engaging the shank of the foremost tack in said feed slot to tilt the same whereby its head will be raised above the head of the next succeeding tack in the event it was overlapping the same.

4. A tack dispenser comprising a closed receptacle having upper and lower chambers, said lower chamber projecting outwardly beyond said upper chamber along one side thereof, a baffle plate enclosing the outwardly projecting portion of the lower chamber and extending inwardly between said chambers to substantially the middle thereof, a readily removable slotted tack receiving and aligning plate mounted intermediate the sides of said lower chamber and below said baffle plate, said aligning plate having a series of spaced slots adapted to support a plurality of tacks by their heads with their shanks depending therethrough, said slots being open along one end into a common feed slot, a dispensing opening in the outwardly projecting portion of said baffle plate, said opening being in alignment vertically with said feed slot, and a tilter mounted below said feed slot in substantial alignment with said dispensing opening adapted to engage the shank of a tack being moved therewith causing its head to be tilted forwardly

to disengage the head of the next succeeding tack if it should be overlapping.

5. A tack dispenser consisting of a closed receptacle having upper and lower chambers, said 5 lower chamber projecting outwardly beyond said upper chamber along at least one side thereof, a support intermediate the sides of said upper chamber for receiving a box of tacks, a baffle plate enclosing the outwardly projecting portion of the lower chamber and extending inwardly between said chambers, a readily removable tack receiving and aligning plate mounted intermediate the sides of said lower chamber and below said baffle plate having a series of spaced tack 15 receiving slots which are in open communication along one end with a feed slot, a dispensing opening aligned with and spaced above said feed slot of a size sufficient to permit the withdrawal of one tack at a time from said receptacle, and 20 an adjustable tilter mounted below said feed slot in substantial alignment with said dispensing opening adapted to engage the shank of a tack being moved therewith causing its head to be tilted forwardly to disengage the head of the next succeeding tack if it should be overlapping.

6. A tack dispenser consisting of a closed receptacle having upper and lower chambers, means for opening said upper chamber to insert a box of tacks therein, means for opening said lower chamber to remove defective tacks therefrom, said lower chamber projecting outwardly beyond said upper chamber along at least one side thereof, a support intermediate the sides of said upper chamber for receiving a box of tacks and supporting it above said baffle and slotted plates, a baffle plate enclosing the outwardly projecting portion of the lower chamber and extending inwardly between said chambers, a readily removable tack receiving and aligning plate mounted intermediate the sides of said lower chamber and below said baffle plate having a series of spaced tack receiving slots which are in open communication along one end with a feed slot, a dispensing opening aligned with and spaced above said feed slot of a size sufficient to permit the withdrawal of one tack at a time from said receptacle, and an adjustable tilter mounted below said feed slot in substantial alignment with said dispensing opening adapted to engage the shank of a tack being moved therewith causing its head to be tilted forwardly to disengage the head of the next succeeding tack if it should be overlapping.
